US0D1049183S

(12) **United States Design Patent** (10) Patent No.: **US D1,049,183 S**
(45) Date of Patent: ** Oct. 29, 2024

(54) **3D PRINTER**

- (71) Applicant: **Shenzhen Creality 3D Technology Co., Ltd.**, Shenzhen (CN)
- (72) Inventors: **Jingke Tang**, Guangdong (CN); **Zhiqiang Yang**, Guangdong (CN); **Jian Deng**, Guangdong (CN)
- (73) Assignee: **Shenzhen Creality 3D Technology Co., Ltd.**, Shenzhen (CN)

(**) Term: **15 Years**(21) Appl. No.: **35/517,769**(22) Filed: **Jul. 14, 2022**(80) **Hague Agreement Data**

Int. Filing Date: **Jul. 14, 2022**
Int. Reg. No.: **DM/223071**
Int. Reg. Date: **Jul. 14, 2022**
Int. Reg. Pub. Date: **Jul. 14, 2023**

(57) **CLAIM**

The ornamental design for a 3D printer as shown and described.

DESCRIPTION

- 1.1: Perspective
1.2: Perspective
1.3: Front
1.4: Back
1.5: Left
1.6: Right
1.7: Top
1.8: Bottom

The design includes a printing platform assembly and a printing head assembly; and the printing head assembly is used to print 3D models on the printing platform assembly. The broken lines in the drawings depict portions of the 3D printer and form no part of the claimed design.

1 Claim, 8 Drawing Sheets
